ABSTRACT OF THE DISCLOSURE

A rubber band motor for a toy truck or other toy vehicle, which efficiently utilizes an ordinary rubber band. The motor includes a tapered receiving portion fixed to one vehicle axle, and the rubber band is positioned to wind onto the axle around the tapered portion so that the band is wound more slowly as it becomes highly stretched. Band-engaging posts on the axle and frame enable an ordinary rubber band to be mounted by merely slipping it over two posts. Several posts are provided on the frame to enable rubber bands of various lengths to be efficiently utilized.

BACKGROUND OF THE INVENTION

(1) Field of the invention

This invention relates to toy vehicles and, more particularly, to rubber band type drives therefor.

(2) Description of the prior art

One type of motor driven toy vehicle employs a band of rubber or other elastic material having one end fixed to the vehicle frame and the other end coupled to an axle of the vehicle. When the vehicle is rolled backward, the band winds around the axle to propel the vehicle forward when it is released. A clutch is generally employed to couple one end of the band to the axle, so that the axle and wheels thereon can continue to roll forward after the band is completely unwound. The rubber band motors are generally incapable of efficiently utilizing the motive power which can be applied by a rubber band. This is because the band is in such high tension when fully wound that it can spin the wheels before the vehicle starts moving rapidly forward, so that much of the power is lost. If the axle is made very narrow to prevent wheel spinning, it cannot efficiently utilize the last portion of the band to be unwound, this last portion having only a low tension.

Inasmuch as rubber bands break frequently, it is desirable to enable a child to quickly replace a broken band with another household rubber band. However, while rubber bands of about three inches in length are commonly available, a child often cannot find a band of the exact length necessary for most efficient operation of the toy. If the band is too long, it cannot be easily mounted, while if it is too short, it is partially stretched during mounting and cannot be wound as far.

OBJECTS AND SUMMARY OF THE INVENTION

An object of the present invention is to provide a toy vehicle with an elastic band motor which efficiently utilizes the motive power of the band.

Another object of the invention is to provide a rubber band powered toy vehicle which readily accepts and efficiently utilizes rubber bands of different unstretched lengths.

In accordance with the present invention, a toy vehicle is provided which has a motor that efficiently utilizes an elastic band for propelling the vehicle. The vehicle includes a pair of wheels mounted on an axle, and a rubber or other band that winds around the axle when the wheels are rotated backward and which propels the vehicle forward when it is released. The axle includes a ta-

2

pered band-receiving portion, and the elastic band is mounted so that it first winds around the largest diameter part and thereafter on constantly decreasing diameter parts of the tapered portion. As a result, when the band is fully wound it is on a narrow diameter axle portion to supply a minimum torque so that the wheels are not accelerated too fast and do not spin on the ground. During the last period of unwind, when the elastic band tension is low, it is turning a large diameter portion of the axle to enable efficient utilization of the band. The tapered construction assures a smooth transition between the beginning and end of band unwind.

The vehicle is constructed to allow a child to install an ordinary household rubber band thereon when the previous rubber band breaks. Both the vehicle frame and axle have posts which enable a rubber band to be installed by merely looping its opposite ends over the posts. The vehicle frame is provided with several posts spaced at different distances from the posts on the axle, so that a rubber band which is slightly shorter or slightly longer than average can be efficiently utilized. A child loops one end of the rubber band over that post on the frame which establishes the band in a very slightly stretched state when the motor is completely unwound.

The novel features of the invention are set forth with particularity in the appended claims. The invention will be best understood from the following description when read in conjunction with the accompanying drawings.

BRIEF DESCRIPTION OF THE DRAWINGS

FIG. 1 is a perspective view of a toy truck which utilizes an elastic band motor constructed in accordance with the invention:

FIG. 2 is a bottom view of the toy truck of FIG. 1, with the motor in an unwound state;

FIG. 3 is a view similar to that of FIG. 2, with the motor in a fully wound state;

FIG. 4 is a sectional view taken on the line 4—4 of FIG. 2;

FIG. 5 is a partial sectional view taken on the line 5—5 of FIG. 2; and

FIG. 6 is a partial sectional view taken on the line 6—6 of FIG. 2.

DESCRIPTION OF THE PREFERRED EMBODIMENTS

FIG. 1 illustrates a toy vehicle which includes a frame 10, four wheels 12, 14, 16 and 18, and a rubber band motor 20 for propelling the vehicle. As shown in FIG. 2, the rear wheels 16, 18 are fixed to an axle 22 that is rotatably mounted on a pair of brackets 24, 26 that are fixed to the vehicle frame. The axle 22 is part of an axle assembly 27 that is adapted to receive a rubber band 28. The rubber band has one end 31 fixed to a post 30 on the frame and an opposite end 29 coupled to the axle assembly 27. A child can wind the motor by moving the truck backward along the ground, to turn the axle assembly in the reverse direction so that the rubber band winds thereon as shown in FIG. 3. When the child releases the truck, the rubber band unwinds from the axle assembly, spinning the axle to propel the truck in a forward direction.

The axle assembly includes a band receiving portion 32 which is fixed to the axle 22 and a start portion 34 which is rotatably mounted on the axle. The start portion 34, to which one end 29 of the rubber band is attached, has a clutch face with a tooth that can engage a corresponding clutch tooth on the band-receiving portion 32 to drive the band-receiving portion in a forward direction. During backward rolling of the truck to wind the rubber band motor, the wheels drive the receiving portion 32 in a reverse direction, and it drives the start portion

34 in a reverse direction to wind the rubber band. When the truck is released, the rubber band turns the receiving portion 32 and start portion 34 in a forward direction to accelerate the truck to a substantial speed.

When the truck reaches its maximum speed, the rubber band is completely unwound and the start portion 34 cannot turn in the forward direction any further. If the start and receiving portions 34, 32 were fixed together, the truck would suddenly come to a halt. However, the clutch teeth on these portions allows the receiving portion 32 to continue to rotate forward, while the clutch teeth on the portions 32, 34 slip on each other. Accordingly, the truck can roll a considerable distance in the forward direction.

As also shown in FIGS. 5 and 6, the start portion 34 of the axle assembly has four posts 36, 38, 40, 42 arranged along a circle having approximately the same circumference as the largest portion of the axle assembly. The end 29 of the rubber band can be slipped over any one of the four posts to attach it to the start portion. The four posts serve as a guard to prevent the rubber band from starting to wind around the narrow diameter axle 22 instead of winding along the band receiving portion 32. The band receiving portion 32 has a tapered region 44 which has a largest diameter end 46 nearest the starting portion 34 and a narrowest diameter portion 48 furthest from the start portion 34. Thus, as the rubber band 28 is wound on the axle assembly, the first portions are wound around the large part of the tapered region while successive portions are wound around areas of successively decreasing diameter.

The use of a tapered region on the band receiving portion 32 promotes efficient use of the rubber band. When the truck is released after winding the band, the band is initially at a high tension and rapidly accelerates the truck. The first portions of the band to be unwound should unwind from a narrow diameter region so that the band can supply only a relatively small torque to the axle 22. If the first portions to unwind were to contact a large diameter region of the axle assembly, they could accelerate the wheels so fast that the wheels would slip on the ground. In such a case, much of the motor power would be wasted. However, in the motor of this invention, the first portion 50 of the band to unwind contacts a narrow diameter part of the axle assembly. Thus, the rubber band initially applies only a moderate torque, and the wheels do not slip.

The last portions of the rubber band to be unwound from the axle assembly, should contact a large diameter part of the axle assembly. This is because the rubber band is at a low tension at the end of unwinding and cannot apply a large force. By applying the small force available near the end of unwinding to a large diameter portion of the axle assembly, the small force can still supply a substantial torque to further accelerate the truck so it attains an even higher speed.

The post 30 around which the end 31 of the rubber band extends is positioned at one side of the vehicle frame. This causes the rubber band 28 to extend in a direction to urge the start portion 34 of the axle assembly toward engagement with the receiving portion 32 of the assembly, to assure their engagement during winding of the band. In addition to post 30, two other posts 52, 54 are provided which are at different distances from the start portion 34. The provision of three posts at different distances from the start portion 34 enables the efficient use of rubber bands of a range of sizes. This is important because the rubber band initially supplied with the vehicle may break and have to be replaced. The toy is designed so that a child may utilize an ordinary household rubber band, which may range in length between limits such as 2 3/4 inches and 3 1/4 inches. The child attaches the band to one of the posts 30, 52 or 54 which provides just enough tension to keep the band in place. If a post is used which is too close to the axle assembly, the band

is likely to fall off, while if a post is used which is too far, the band will be initially stretched and it cannot supply a maximum amount of power. The provision of several posts allows for mounting at a nearly optimum distance.

5 The motor can be wound by grasping one of the wheels 16 or 18 and turning it backwards. However, a person is then likely to overwind the motor and break the band. It is generally preferable to wind the motor by rolling the vehicle backward on the ground. The wheels 16, 18 10 may be constructed of a hard plastic which has a relatively low coefficient of friction so it can readily spin on the ground. When a child presses down on the vehicle with only moderate force while rolling it backwards, the wheels will slide on the ground after the motor is wound sufficiently, so that further backward movement of the vehicle will not overwind the band and break it. Of course, it is possible to press down hard enough on the vehicle to still break the band during backward rolling, but this is less likely to occur than with hand turning.

20 Thus, the invention provides a toy vehicle which efficiently utilizes the motive power which can be supplied by an elastic band. The vehicle has an axle assembly with a tapered portion for receiving the elastic band to minimize the torque supplied when the band is fully wound, so as to prevent wheel slippage. This is especially important for vehicles with wheels which are made to slip easily to prevent overwinding. The tapered portion of the axle assembly also enables even the last portions to be unwound, of the rubber band, to contribute to vehicle acceleration. The members which hold the band are constructed to allow an ordinary loop-shaped household rubber band to be easily mounted thereon, and to allow efficient utilization of rubber bands within a range of sizes. Many variations in the construction of the vehicle can be employed to increase performance. For example, it is possible to utilize a front axle which is similar to the rear axle, and to allow the rubber band to extend between starting portions on the two axles so 30 that all four wheels accelerate the truck.

35 Although particular embodiments of the invention have been described and illustrated herein, it is recognized that modifications and variations may readily occur to those skilled in the art, and consequently, it is intended that the claims be interpreted to cover such modifications and equivalents.

40 What is claimed is:

1. A toy vehicle comprising:

a frame;
50 an axle assembly rotatably mounted on said frame, including an axle having a first end, a second end and an intermediate portion, a tapered, band-receiving portion fixed on said axle, said band-receiving portion having a small-diameter end adjacent said first end of said axle and a large-diameter end adjacent said intermediate portion of said axle, and a start portion rotatably mounted on said axle adjacent said large-diameter end of said tapered portion; wheel means attached to said axle to rotate with it; first means for coupling one end of an elongated elastic

55 member to said start portion, said first means for coupling comprising a plurality of axially-extending posts mounted on said start portion and arranged in a circle of a diameter at least about as large as the larger diameter end of said tapered portion, said posts extending axially over said second end of said axle, whereby said posts serve as a guard preventing said elastic member from winding about said second end of said axle;

60 second means for coupling a second end of said elastic member to said vehicle so that the elastic member extends with a directional component angled toward the small-diameter end of said tapered portion whereby rotation of said axle assembly causes said elastic member to pull said start portion into engagement with a second end of a third member of a second

ment with said large-diameter end of said tapered portion and to wind on portions of said tapered portion of progressively smaller diameter; and

one-way clutch means on said start portion and said large-diameter end of said tapered portion in facing relationship for forming a driving connection when said elastic member is wound on said tapered portion.

2. The toy vehicle described in claim 1 wherein:

said second means for coupling comprises a plurality of posts mounted on said frame at different distances from said large diameter end of said tapered receiving portion of said axle assembly, whereby to hold firmly, but without substantial initial stretching, elastic members of different unstretched lengths.
